UNITED STATES PATENT OFFICE.

JOHN S. JEFFREY, OF COLUMBUS, OHIO.

RAILWAY-SIGNAL.

No. 822,951.

Specification of Letters Patent.

Patented June 12, 1906.

Application filed November 16, 1905. Serial No. 287,424.

To all whom it may concern:

Be it known that I, JOHN S. JEFFREY, a citizen of the United States, residing at Columbus, in the county of Franklin and State 5 of Ohio, have invented new and useful Improvements in Railway-Signals, of which the following is a specification.

This invention is a railway signal device, and more particularly one for signaling a car 10 to stop.

The device is especially adapted for inter-urban electric roads, its object being to save persons wishing to signal a car to stop the trouble and danger of standing on or near the track where they can be seen by the motor-man, especially at night and during bad weather. The signal device will be placed at 15 the stopping places or stations along the road and is set by the person wishing to board a 20 car.

The invention also comprises means actuated by the car-wheels for withdrawing the signal.

In the accompanying drawings, Figure 1 is 25 an elevation, partly diagrammatic, of the invention. Fig. 2 is a similar view showing the position of the parts when the signal is set.

Referring specifically to the drawings, 5 30 denotes a post which is placed a suitable distance from the track. At the top of the post is secured a plate 6, to which is pivoted, as at 7, a vertically-swinging arm 8, which carries at one end a flag or other suitable visual signal 9 and at the opposite end a weight 10, which is adjustable along the arm, being secured in adjusted position by a set-screw 11. The weight serves to normally hold the arm 8 35 in upright position, as shown in Fig. 1, in 40 which position the signal is withdrawn. To set the signal, the arm is swung down into horizontal position, as shown in Fig. 2, by pulling on a rope 12, attached to the arm. This throws the flag outwardly close to the 45 track, so as to be readily visible to the motor-man of the approaching car, thus notifying him that a person wishes to board the car. If desired, the rope can be run into the shelter-shed, thus rendering it unnecessary to 50 leave the same to set the signal.

The means for holding the arm 8 in horizontal position and preventing the weight from swinging it back to its upright position 55 comprises a dog 13, which is pivoted at 14 to the plate 6. One end of the dog is weighted, as at 15, and its other end enters the notch 16

in the periphery of a disk 17, carried by the arm 8 and concentric with its pivot. When the dog is released from the notch, the weight 10 causes the arm to swing back to its upright position. The dog is connected by a draw-rod 18 to one arm of a bell-crank lever 19, which is fulcrumed, as at 20, near the bottom of the post 5. The other arm of the bell-crank lever is connected by a draw rod 21 to 65 one of the arms of a second bell-crank lever 22, which is fulcrumed at 23 to the side of the tie 24, which supports the track-rails, one of the latter being shown at 25. Adjacent this rail is a tripper 26, working in a stirrup 27, 70 secured to the tie and so located with respect to the rail as to be depressed by the flange of the car-wheels. The lower end of the tripper is connected, as at 28, to the bell-crank 22. A stop-pin 29, projecting from the side 75 of the tie 24, limits the swing of the bell-crank lever 22, and thus prevents the tripper from being pushed upwardly too high for its successful operation. The connections between the tripper and the dog cause the latter to swing away from the notch 16 when the tripper is depressed in the manner stated, which releases the arm 8 and leaves it free to be swung back by the weight 10 into upright 80 position whereby the signal is withdrawn. A 85 stop-pin 30 projects from one side of the post 5 and limits the downward swing of the weighted end of the arm 8.

The device so far described is for signaling in the day-time. For night-time a red light 90 is employed, which may be an electric lamp 31, carried by a bracket 32, extending outwardly from the top of the plate 6 toward the track. The light is turned on and off by the swing of the arm 8, it being on when the arm 95 is down and off when the arm is up. This control of the light is had by a switch carried by the arm, said switch comprising a metal strip 33, secured to the arm, but insulated therefrom. The strip is so located that it 100 bridges two contacts 34 on the plate 6 when the arm is down, and thus closes the electric circuit containing the light, the wires leading from the contacts to the light being indicated at 35.

The signal device herein described is simple in construction and has no complicated parts to get out of order, and it can be installed at a small cost. It effectively serves the purpose for which it is intended. It operates as well at night as in the day.

Having thus described my invention, what

is claimed as new, and desired to be secured by Letters Patent, is—

1. A railway-signal comprising a manually-operated swinging arm carrying a signal device, and car-operated means to withdraw the signal.
2. A railway-signal comprising a manually-operated swinging arm carrying a signal device, a latch for holding the arm when the signal is set, and means operated by a car for releasing the latch to withdraw the signal.
3. A signal comprising a manually-operated vertically-swinging arm displaying a signal device when lowered, means for elevating the arm to withdraw the signal, a latch for holding the arm in lowered position, and car-operated means for releasing the latch.
4. In a railway-signal, the combination with a support, carrying an electric signal-light and circuit-contacts therefor, of a ver-

tically-swinging arm pivoted to the post and carrying a switch engaging the contacts to close the circuit when the arm is down, a latch for holding the arm in lowered position, means for elevating the arm, and car-operated means for withdrawing the latch. ²⁵

5. In a railway-signal, the combination with a swinging arm carrying a signal device, of an electric signal-light, and means for closing the circuit of said light when the signal device is set, and opening the circuit when the signal device is withdrawn. ³⁰

In testimony whereof I have signed my name to this specification in the presence of two subscribing witnesses.

JOHN S. JEFFREY.
